UNITED STATES PATENT OFFICE.

HERBERT ARTHUR ACKERET, OF MASSILLON, OHIO, ASSIGNOR TO THE MASSILLON-CLEVELAND-AKRON SIGN COMPANY, OF MASSILLON, OHIO, A CORPORATION.

ADVERTISING CUT-OUT DEVICE.

Application filed November 13, 1924. Serial No. 749,770.

To all whom it may concern:

Be it known that I, HERBERT ARTHUR ACKERET, a citizen of the United States, residing at Massillon, in the county of Stark 5 and State of Ohio, have invented certain new and useful Improvements in Advertising Cut-Out Devices, of which the following is a specification.

The present invention relates to a cut-out device for use in advertising bottled products, being more particularly adapted for the advertising of soft drinks, although with obvious modifications it can be adapted for use in advertising and displaying any 15 kind of a product that is put up in bottles.

Among the objects of the invention are to provide a device of this character which can be inexpensively cut or stamped from sheet material, such as card-board, and 20 which when applied to a bottle or like container will simulate a human figure or animal straddling the upper end of the bottle and drinking the bottle contents or surveying the same with approval.

One particular design of the cut-out device has been shown and described for illustrative purposes, although it will be understood that various forms of designs can be used and that the cut-out device may 30 represent a boy, girl, or any kind of a human figure, or any kind of an animal that may be adapted for the purpose, the particular design which is used depending upon the character of the goods being advertised and 35 also upon the personal ideas and caprices of the advertiser.

For a full understanding of the invention reference is to be had to the following description and accompanying drawings, in 40 which,

Figure 1 is a plan view of a cut-out device which embodies the invention, showing the same in the flat form in which it is received for use.

Figure 2 is a front elevation of the same cut-out device, showing the same as applied to the neck of a bottle, and

Figure 3 is a side elevation thereof.

Corresponding and like parts are referred 50 to in the following description and indicated on all of the views of the drawings by like reference characters.

Referring to the drawing which illustrates one of many possible forms of the

invention, the reference character A designates the cut-out device as a unit, and B the bottle to which the cut-out device is applied. The cut-out device is adapted to be formed of sheet material such as card-board, sheet metal or the like, and the bottle B is of the 60 form and size which is quite generally used for the popular kinds of soft drinks, the upper end of the bottle being tapered and converging into a reduced neck. The cut-out device is suitably shaped and marked, 65 so that it simulates a human being or animal of some kind, and when applied to the upper end of the bottle the human being or animal has the appearance of straddling the 70 bottle with its legs and clasping its arms or paws around the neck of the bottle. The particular form of cut-out device which has been illustrated is shaped and marked to simulate a boy, although it will be understood that the particular design is immaterial and that the cut-out device may be shaped and marked to simulate any human figure or any animal which might be appropriate.

The numeral 1 designates the body portion of the cut-out device, said body portion being provided at the bottom thereof with the legs 2, and having a head portion 3 at the top thereof. The legs 2 spread apart a considerable amount and have a rounded 85 crotch portion 4 between the same which is of a suitable size and curvature to fit around the tapered upper end of the bottle. The feet 5 are inturned so that they will engage the front of the bottle and serve to hold the 90 lower end of the cut-out device in proper position, giving the legs the appearance of straddling the bottle and clinging thereto by means of inturned toes.

The arms 6 are cut from the body portion and extend inwardly toward each other, being shown in the present instance as terminating in the clasped hands 7. The arms and clasped hands are cut out from the body portion and form in effect a transverse 100 strip which can be deflected forwardly to permit of the bottle neck being inserted between the arms and the body portion, thereby causing the figure of the cut-out device to have the appearance of hanging on to the 105 neck of the bottle by throwing its arms around the same and clasping its hands. The thumbs 8 of the hands are shown as

projecting upwardly so as to be of assistance in engaging the bead 10 at the upper end of the bottle neck 11.

Where the device is used upon a bottle containing a soft drink or potable substance, a straw 12 or like element may be pictured as extending downwardly from the mouth so that it will have the appearance of entering the neck of the bottle. When 10 the device is applied to the bottle the human figure or animal which is pictured by the design will have the appearance of clinging to the neck of the bottle and drinking the contents thereof through the straw 12.

15 These cut-out devices can be readily cut or stamped from any suitable sheet material such as card-board or sheet metal and can be packed flat for shipment, thereby enabling them to be inexpensively manufactured and 20 distributed. In order to use the same it is merely necessary to deflect the hands forwardly and insert the neck of a bottle between the hands and the body of the device, at the same time causing the crotch between 25 the bowed legs to fit around the tapered upper end of the bottle. The device is easily and quickly applied to a bottle, and provides a very effective means for displaying the same and attracting attention thereto. Where 30 the term "human figure" is used in the specification and claims it will be understood that this term is to be construed broadly and is meant to include any analogous or equivalent representation, such as the representation 35 of any suitable kind of an animal.

Having thus described my invention what I claim as new and desire to secure by Letters Patent is—

1. A cut-out device for advertising bottled

products, including a body portion cut from sheet material and shaped and marked to simulate a human figure, said figure having arm portions which are connected at their inner ends and cut out along their upper and lower edges to provide a transverse strip which can be deflected from the plane of the body portion to permit of the bottle neck being inserted between the strip and body portion, the figure also having cut-out legs which are separated by a crotched portion 40 adapted to fit around the bottle below the portion thereof engaged by the arms, the device being adapted to give the appearance of a figure clinging to the bottle by means of 45 its arms and legs.

2. A cut-out device for advertising bottled products, including a body portion cut from sheet material and shaped and marked to simulate a human figure, said figure having cut out legs separated by a crotched portion which is adapted to fit around a portion 50 of the bottle and give the legs the appearance of straddling the bottle, the figure also having arm portions connected at their inner ends by hands and cut out along their upper and lower edges to provide a transverse strip which can be deflected from the plane of the body portion to permit of the bottle neck being inserted between the strip and the body portion, the hands being 55 formed with cut-out thumb portions which project upwardly and are adapted to engage the exterior bead of the bottle neck to assist in holding the device in position upon the 60 bottle.

In testimony whereof I affix my signature.

HERBERT ARTHUR ACKERET.
